AIR FLOATED BARGE

Filed Sept. 14, 1925

2 Sheets-Sheet 2

A technical line drawing of a mechanical assembly. The drawing shows a base structure with a central vertical column. A horizontal plate is attached to the left side of the column. The right side of the column features a curved, ribbed section. Several labels are present: '26' is on the left side of the base; '82' is at the top left; '92' is at the top right; '102' is on the right side of the ribbed section; '26' is again on the far right; and '104' is at the bottom right. The drawing is done in a style typical of early 20th-century engineering blueprints.

UNITED STATES PATENT OFFICE.

VASCO F. CASEY, OF MINNEAPOLIS, MINNESOTA.

AIR-FLOATED BARGE.

Application filed September 14, 1925. Serial No. 56,189.

This invention relates to the flotation of boats or vessels, and more especially of those of the flat bottom type usually designated as barges, and has for its object to reduce 5 to a minimum the friction due to travel of the boat through the water.

It is a known fact that, in all boats or vessels, and especially in boats of the barge type, which have flat or substantially flat 10 bottoms and very shallow water draft, the water friction in the travel of the boat is very great, due to the large amount of "wet surface."

In accordance with my invention, I reduce 15 this water friction to a minimum by floating the barge or boat directly upon a sheet of air. Moreover, by forcing the circulation of this sheet of air in a rearward direction under the bottom of the boat, I obtain a 20 forwardly propelling action that, in effect, does more than overcome frictional water resistance to the forward travel of the boat and actually produces a forward travel of the boat. I do not, however, generally propose 25 to rely solely on this forward propelling action of the circulated air sheet, but will use any of the well known propelling devices, such as paddle wheels, screw propellers or the like, as the primary propelling means. 30 Of course, energy will be required to maintain and circulate or rearwardly propel the sheet of air used to float the boat, but well known methods of calculation clearly show that a very much less total expenditure of 35 energy, applied as above indicated, will be required to propel a boat of a definite size at a definite speed than is required to propel the same boat at the same speed by the older methods wherein the boat is subject to the 40 customary water friction and all of the energy used for direct propulsion.

The invention is illustrated in the accompanying drawings, wherein like characters indicate like parts throughout the several 45 views.

Referring to the drawings:

Fig. 1 is a plan view with some parts broken away, illustrating my invention applied to an ordinary barge or flat bottom boat; 50 Fig. 2 is a view partly in side elevation, but chiefly in section on the line 2—2 of Fig. 1;

Fig. 3 is a transverse section on the line 3—3 of Fig. 1;

Fig. 4 is a plan view showing my invention applied to a barge and illustrating a

somewhat modified application of the invention;

Fig. 5 is a side elevation of the barge shown in Fig. 4; 60

Fig. 6 is a fragmentary view partly in side elevation and partly in section on the line 6—6 of Fig. 4; and

Fig. 7 is an enlarged transverse section on the line 7—7 of Fig. 4. 65

Referring first to the construction illustrated in Figs. 1, 2 and 3, the numeral 8 indicates the barge or flat bottom boat. In accordance with my invention, the bottom of this barge is formed with a plurality of 70 longitudinal open bottom air channels 9 formed between depending flanges 10 shown as in the form of angle bars rigidly secured to the bottom of the boat and extended longitudinally thereof but terminating 75 slightly short of the inclined front and rear bottom portions of the barge. Here it may be noted that the bottom of the boat, just in front and at the rear of the channels 9, extends down to the bottoms of the flanges 80 10, as indicated at 11, so that the extreme ends of the channels 9 are closed but, of course, leaving the entire bottoms of the channels 9 open against the water.

In the scheme here illustrated, the air is 85 arranged to be circulated over and over through the channels 9, and for this purpose I provide for each channel 9 an air-circulating pipe 12 located at some convenient place within the barge. The air pipes 12 are provided with flattened and transversely expanded front ends 13 that open directly into the front ends of the respective air channels 9, and said pipes at their rear ends are provided with similar flattened and transversely 95 expanded portions 14 that are connected directly to the rear ends of the respective air channels 9. For the circulation of air through the air pipes 12 and channels 9, I provide primary air-propelling devices 100 preferably in the form of fans or blowers 15 that are interposed in the respective pipes 12. The rotors of these blowers 15 are, as shown, all connected to a common transverse shaft 16 arranged to be driven through a belt 105 17 from a motor 18 carried by the barge. As already indicated, this motor will circulate the air through the channels 9 immediately under the bottom of the boat in a rearward direction, and the amount of air 110 circulated will be sufficient to keep a sheet of air in each channel 9 immediately adjacent

to the bottom of the boat, leaving the bottoms of the channels 9 sealed with water. Of course, in forcing the air rearwardly under the bottom of the boat, there will be 5 a reaction tending to propel the boat forward, and this reaction will more than overcome the slight water resistance. The main portion of the boat is thus floated on air and the air, of course, offers a very slight resistance to the movement of the boat. The wet surface is reduced to a minimum and its friction, as indicated, is more than overcome 10 or offset by the tendency to propel the boat forward.

15 In the above described arrangement, wherein the air is circulated in a continuous course over and over again under the bottom of the boat, there will be more or less leakage of air and leakage of air would reduce 20 the thickness of the sheet of air maintained under the bottom of the boat and more or less water would displace the lost air and would ultimately get into the air-circulating pipe. To prevent this, I preferably provide 25 auxiliary fans or blowers 19, one for each circulating pipe 12. These blowers 19 are provided with air discharge pipes 20 that open obliquely into the air pipes 12 at points 30 on the receiving sides of the corresponding blowers 15 and incline in the direction of the travel of the air through said pipes. The rotors of these blowers 19, as shown, are carried by a common transverse countershaft 21 that is driven through a belt 22 35 from a motor 23 suitably mounted on the barge. It is the intention that the secondary or auxiliary blowers 19 should be operated at a speed sufficient to maintain the air sheets in the several channels 9 and that 40 the blowers 15 should be called upon only to circulate the air in the direction indicated. In the branch pipes 20 are applied check valves 24 preferably of the flapper valve type, which freely permit the discharge of 45 air from the blowers 19 to the air pipes 12, but check a reverse flow through said branch pipes.

With the arrangement just described, the 50 air confined in the channels 9 will engage nearly the entire bottom of the barge and, obviously, the barge may be propelled forwardly on the supporting air under very slight resistance and the reaction from the 55 discharge of air through the channels 9 will tend to propel the boat forwardly or at least will offset the resistance due to the slight "wet surface", due to direct contact between the water and small areas of the 60 barge.

By confining the air under the bottom of the boat to travel in several laterally spaced channels, listing of the boat laterally, due to over-accumulation of air at one side of the 65 boat, is prevented. To prevent rushing of

the air and too great accumulation thereof either at the front or rear end of the boat, the air channels 9 are provided with longitudinally spaced depressions 25 which are arranged to be always somewhat above the 70 level of the water in the respective channels 9.

In the modified construction illustrated in Figs. 4, 5, 6 and 7, the air is circulated from the front toward the rear under the 75 bottom of the boat, but is not returned. In this arrangement, the barge 8^a on its bottom is provided with longitudinally spaced depending flanges 10^a that form air channels 9^a under the bottom of the barge. These channels 9^a have longitudinally spaced depressions 25^a that correspond in character and function to the depressions 25 of the structure first described. At the rear extremities of the channels 9^a, the bottom of the barge is formed with depressions 26, under and past which the air channels 9^a and flanges 10^a are extended so that air from the channels 9 will be discharged at the stern or rear of the boat. In this arrangement, blowers or fans 15^a are provided with discharge spouts 12^a that deliver air into the front ends of the channels 9^a. The rotors of these blowers 15^a, as shown, are driven 80 from a motor 18^a through a countershaft 27, belts 28 and 29, and pulleys 30, 31, 32 and 33. In the arrangement last described, air from the channels 9^a will be discharged under the inclined stern of the barge, so that the air, 85 in escaping, produces a forward propulsion of the boat, both by the reaction against the water and the upward movement thereof against the said inclined stern.

As before stated, the boat may be propelled primarily by any suitable propelling means. In Figs. 4 and 5, I have shown a stern wheel propeller 34 driven from a motor 35 through a countershaft 36, sprocket chains 37, belt 38, and cooperating sprocket 90 wheels and pulleys.

What I claim is:

1. A boat equipped with means for maintaining under the bottom thereof a sheet of air on which the boat is floated, and means 115 for maintaining an endless circulation of the air and for forcing rearwardly the air on which the boat is floated.

2. A boat having an approximately flat bottom formed with longitudinal air channels open at their bottoms against the water, in combination with power-driven means for forcing air into the front end portions of said air channels and causing the same to travel rearwardly, the said air channels having longitudinally spaced depressions for the purpose described.

3. A boat having an approximately flat bottom formed with longitudinal air channels open at their bottoms against the water,

power-driven blowers carried by the boat and provided with air discharge pipes that open into the front end portions of said air channels and discharge air in a rearward direction under the bottom of the boat, air return pipes leading from the rear end portions of said air channels to the respective blowers, and secondary blowers delivering into said air return pipes.

4. A boat having an approximately flat bottom formed with longitudinal air channels open at their bottoms against the water, power-driven blowers carried by the boat and provided with air discharge pipes that

open into the front end portions of said air channels and discharge air in a rearward direction under the bottom of the boat, air return pipes leading from the rear end portions of said air channels to the respective blowers, and secondary blowers delivering into said air return pipes.

5. The structure defined in claim 4 in further combination with check valves applied to prevent return flow from said return pipes to said secondary blowers.

In testimony whereof I affix my signature.

VASCO F. CASEY.
